Int. Cl. D6—99

U.S. Cl. D6—85

FIG. 1 is a perspective view of an instrument stand embodying my new design, and illustrating the stand in one of a plurality of normal operating positions;

FIG. 2 is a front elevational view of the instrument stand shown in FIG. 1;

FIG. 3 is a bottom plan view thereof;

FIG. 4 is a rear end elevational view thereof;

FIG. 5 is a side elevational view thereof, illustrating the side opposite that shown in FIG. 1;

FIG. 6 is a bottom plan view of the instrument stand, illustrating the same in a collapsed state; and

FIG. 7 is a fragmentary sectional view, taken along the lines 7—7 of FIG. 6, and illustrating retention means for maintaining the stand in various operative positions.

I claim:

The ornamental design for an instrument stand, as shown.
